Cooper, Kerr & Dunham

UNITED STATES PATENT OFFICE.

ROBERT W. CELLARS, OF DELAWARE, OHIO.

GARMENT.

Application filed March 29, 1923. Serial No. 628,506.

To all whom it may concern:

Be it known that I, ROBERT W. CELLARS, a citizen of the United States of America, residing at Delaware, in the county of 5 Delaware and State of Ohio, have invented certain new and useful Improvements in Garments, of which the following is a full, clear, and exact description.

This invention relates to means for securing upper and nether garments together, as for example children's garments, and its chief object is to provide means which can be easily manipulated to fasten and unfasten the garments and which will withstand rough usage. In carrying out the invention in the preferred manner two belts are employed, one encircling the upper garment at the waist line and permanently secured thereto, and the other encircling the 15 nether garment but removable therefrom. The two belts are connected by loops of stiff wire which may take the form of rings carried by the inner belt and extending through slits in the nether garment for engagement with the outer belt which may be provided with suitable means, as for example an ordinary buckle, to fasten its two ends together.

The embodiment outlined above is illustrated in the accompanying drawing, in which—

Fig. 1 is a view showing a boy's blouse or waist and trousers secured together by means of my improved devices, a part of 35 the outer belt and upper portion of the trousers being cut away to show the inner belt;

Fig. 2 is a detail view, on a larger scale, showing the inner belt and the stiff wire 40 ring secured thereby to the upper garment;

Fig. 3 is a detail section, on the same scale as Fig. 2 and taken on line 3—3 of Fig. 1.

In the construction illustrated the upper 45 garment 10, shown as a child's waist or blouse, is provided with an inner belt 11 stitched or otherwise permanently secured to it at the waist line. This belt may be of any suitable material, as for example 50 the cloth of which the blouse itself is made,

and serves to fasten upon the garment a circumferential series of loops 12, as indicated in Fig. 2, for example, wherein the loop 12 is shown as encircling the belt but held in place thereby and prevented from shifting sidewise by the rows of stitching 13 which also serve to secure the belt to the garment. The loops are preferably made of wire heavy or stiff enough to stand the roughest usage without bending or being otherwise deformed, but they are, however, mounted on the garment "pivotally," so to speak, to permit them to fold flat under pressure and thus prevent injury to the wearer by falls and other accidents. The 60 nether garment 14, shown as a pair of short trousers, is provided at the waist line, near the upper edge, with a circumferential series of vertical slits 15 to receive the wire loops or rings 12, as in Figs. 1 and 3. The 65 outer belt 16 extends around the garment and through the loops as in Fig. 1. Upon reflection it will be seen that the wire loops can be passed through the slits more easily even than a button through a button-hole, 70 and thus can be manipulated by small children; with the further advantage that when the outer belt is in place the loops cannot be "unbuttoned" by rough-and-tumble play. Moreover, although the rigid 75 loops can be manipulated like buttons their capability of folding flat upon the garment makes them as harmless and as little liable to injure the wearer as ordinary buttons.

The invention is described as applied to 80 garments for children but it can be used to advantage on garments for more mature persons. It is also to be understood that the construction illustrated and described herein can be modified without departure 85 from the spirit of the invention as defined by the appended claim. The rings or loops 12 are preferably made of metal wire, but they may be stamped out of sheet metal, or may be made of celluloid or other material of suitable character.

I claim:

In an article of apparel, upper and lower garments, a portion of one overlapping part of the other, a series of loops of fixed form 100

spaced around the underneath part of the one garment, a belt encircling said underneath part and passing through said loops, said belt being secured to said part at the 5 sides of said loops, thereby pivotally attaching said loops to said part, the overlapping portion of said other garment being

formed with slits through which said loops may extend, and a removable outer belt passing serially through said loops outside 10 of said overlapping portion.

In testimony whereof I hereto affix my signature.

ROBERT W. CELLARS.
